WORK SUPPORT

Filed Sept. 4, 1925.

INVENTOR-

George Godden

UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

WORK SUPPORT

Application filed September 4, 1925. Serial No. 54,476.

This invention relates to fastening-inserting machines and is illustrated herein as embodied in a fastening-inserting machine having a work support adapted to present shoes having high heels to the fastening-inserting instrumentalities of the machine for the insertion of a row of slugs parallel to the edges of the toplifts of the heels.

High heels are ordinarily made with a substantial wedge so that the attaching surface and the tread surface of the heel are arranged at a considerable inclination to each other. Since the thimble of a last is positioned with its axis substantially at right angles to the heel-seat surface of the last, it follows that if a shoe upon a last is supported upon a vertical last pin, constituting part of the work support of a fastening-inserting machine, the toplift of the heel will be inclined to the presser plate of the machine at an angle equal to the inclination between the tread surface and the attaching surface of the heel. This angle will vary according to the height of the heel and may be as much as twenty or thirty degrees. The operation of a fastening-inserting machine under these conditions is impracticable since it would put a dangerously great pressure upon the edge of the heel and also would result in the fastenings being inclined excessively.

On the other hand, a factor which adds to the difficulties met in attempting to provide a satisfactory work support applicable to the slugging of high heels is the fact that it is often desired to present the work with the tread face of the heel inclined somewhat, for example three or four degrees, to the presser plate of the machine. This localizes the pressure at the edge of the heel adjacent to the position at which the slug is inserted, and tends to prevent bulging of the leather of the top lift adjacent to and between the slugs. It is also causes the fastenings to toe in away from the contour surface of the heel in a manner which is advantageous, for example, in the case of Louis heels.

In view of the foregoing, it is an object of the present invention to provide an improved work support which will present a shoe having a high heel to the fastening-inserting in-

strumentalities of a fastening-inserting machine with the tread surface of the heel either parallel to the presser plate of the machine or, if desired, at a slight angle to the presser plate so as to localize the pressure at the edge of the heel and to direct the fastenings somewhat away from the contour surface of the heel, and which will maintain the parallel or slightly inclined relation of the tread surface of the heel to the presser plate of the machine unchanged during the insertion of a row of fastenings parallel to the edge of the heel. It is a further object of the invention to provide a work support of this character which will be universal in its applicability to the presentation to a fastening-inserting machine of shoes having the wide variety of heels which are used in the manufacture of shoes.

To facilitate the maintaining of the uniform relation of the tread surface of the heel and the presser plate of the machine during the insertion of a row of fastenings parallel to the edge of the toplift, the work-carrying member of the illustrated machine, is mounted for universal horizontal movement and is arranged so as to be solidly supported substantially in alignment with the line of drive of the fastenings so that a tendency, which otherwise would exist to tilt the work and the work support as each fastening is inserted, is eliminated. Stated more specifically, the work support of the illustrated machine comprises a rod having a last pin rigidly connected to its upper end but adjustable throughout a considerable angle. This rod, which may itself be adjusted either to a vertical or to a somewhat inclined position, is supported by a table carried by the horn shaft of the machine and bears upon the table substantially in alignment with the line of drive of the fastenings. Suitable means is provided for permitting bodily horizontal movement of the rod and last pin in any direction over the surface of said table as well as to permit rotary movement of the rod about its axis, while restraining the rod from tilting. In the insertion of a row of fastenings parallel to the edge of the toplift of a heel, the work, as well as the last pin and rod,

moves first bodily in a direction parallel with the lateral edge of the heel. Then, as the fastenings are inserted about the rear of the heel, the work, the last pin and rod rotate, and finally as the fastenings are inserted along the other side of the heel, the work, the last pin and the rod are again moved bodily parallel to the edge of the heel. High heels have comparatively small toplifts and accordingly the bodily movement of the last pin and rod is small and is not such as to move the bearing of the rod upon the supporting plate substantially out of alignment with the line of drive of the fastenings.

With the above and other objects and features in view, the invention will now be described in connection with the accompanying drawings and pointed out in the claims.

In the drawings,

Fig. 1 is a side elevation and Fig. 2 is a front elevation of the fastening-inserting instrumentalities and of the work support of a fastening-inserting machine embodying the present invention with a shoe supported for the insertion of slugs in the toplift of its heel.

The illustrated machine is provided with a presser plate 8, against which is pressed the tread surface of the heel of a shoe to be slugged, and with an edge gage 9 arranged to guide the work as the fastenings are inserted. The machine is also provided with an awl 10 arranged to penetrate and feed the work and with a throat member or driver guide 12 and a driver 14 reciprocated therethrough to insert fastenings. These parts may be of any desired construction and may be operated in any desired manner, for example as shown in Letters Patent of the United States No. 786,190, granted March 28, 1905, on an application of Louis A. Casgrain.

The frame of the illustrated machine is provided with a post or column 16, within which is mounted a vertical sliding shaft 18 controlled by suitable mechanism of well-known character, for example such as that of said Letters Patent No. 786,190, to release the pressure upon the work during the feeding movement of the awl and to clamp the work against the presser plate of the machine during the driving of the fastenings, such mechanism providing substantially uniform clamping pressure irrespective of variations in the thickness of different parts of the work. At its upper end shaft 18 carries a plate 20 securely clamped thereto and provided with an approximately horizontal upper surface 22 which may be slightly dished if desired, and is provided with an elevated rim 24.

Securely clamped to shaft 18 is a block 26 to which a yoke 30 is pivoted about a horizontal axis at 28. Pivoted to yoke 30 at 32 for movement about a horizontal axis at right angles to the pivotal axis of yoke 30 is an upwardly extending arm 34 having se-

cured to its upper end a sleeve 36. To limit the pivotal movement of yoke 30 the latter is formed with a rearwardly projecting finger 38 in the path of movement of which is an adjustable stop 40 carried by block 26. To limit the pivotal movement of arm 34, this arm is provided with a pin 42 passing between a pair of lugs 44, 44 carried by yoke 30. Sleeve 36 carried by the upper end of arm 34 is adjustable about a pivot bolt 46. To facilitate this adjustment, sleeve 36 is formed with a forwardly projecting finger 48 bearing upon an adjustable stop, illustrated as a screw 50, carried by arm 34. Screw 50 may be adjusted to bring sleeve 36 into the desired position with the vertical axis of its bore either vertical or slightly inclined and sleeve 36 may then be locked in that position by tightening up pivot bolt 46.

Mounted for rotary and vertical sliding movement in the bore of sleeve 36 is a rod 52 having its lower end somewhat rounded and supported by and bearing upon plate 20. By reason of the pivotal mounting of arm 34 and yoke 30, rod 52 may be moved bodily in any direction horizontally over the surface of plate 20, such movement, however, being limited by the elevated rim 24 of plate 20. At all times, however, tilting movement of rod 52 is prevented by sleeve 36.

At its upper end rod 52 is formed with a yoke 54 to which is adjustably but rigidly secured by a pivot bolt 56 a bracket 58 formed with a slideway 60 carrying the base block 62 of a last pin 64. Last pin 64 may be clamped in adjusted position relatively to bracket 58 by a bolt 66. In order more firmly to secure bracket 58 in adjusted position, the latter is formed with a serrated surface 68 engaged by a correspondingly serrated surface of a block 70 carried by yoke 54.

In order to limit the relative vertical movement of rod 52 and sleeve 36, rod 52 is formed with a slot 71 arranged to receive a pin 72 which is also received by a horizontal slot 74 formed in sleeve 36 and extending through somewhat more than half its circumference so as to permit the desired rotary movement of rod 52 relatively to sleeve 36. To return the work support to work-receiving position after the pressure has been released upon the conclusion of the insertion of a row of fastenings, a torsion spring 76 is anchored at one end as shown at 78 to sleeve 36 and is secured at the other end to pin 72. As the work is rotated during the insertion of the fastenings spring 76 is tightened and upon the release of the pressure, the torsion of the spring acts to turn rod 52 and last pin 64 into position for the commencement of the insertion of another row of fastenings. Spring 76 serves to prevent the escape of pin 72, being received in a circumferential groove formed about or beneath the head of the latter.

In the operation of the device, bracket 58 is adjusted angularly so as to bring the top-lift of the heel to be operated upon into the desired relation with the presser plate 8 of the machine. In operating upon a high heel the adjustment is preferably such as to cause the edge of the heel to bear upon the presser plate in the manner shown in Fig. 1 with the tread surface of the heel at a slight 10 inclination to the presser plate. Last pin 64 is then adjusted forwardly or rearwardly, if necessary, so that when the heel is properly positioned relatively to the edge gage of the machine the lower end of rod 52 will bear 15 upon and be supported by plate 20 at a point substantially in alinement with the line of drive of the fastenings. With the parts thus positioned a row of fastenings may be inserted parallel to the edge of the toplift with- 20 out disturbing the angular relation of the toplift to the presser plate of the machine. During the operation along the sides of the heel the last pin 64 and rod 52 will move bodily transversely of the machine through a 25 short distance but not sufficiently to bring the bearing of rod 52 upon plate 20 substantially out of alinement with the line of drive. During the insertion of fastenings at the rear of the heel, last pin 64 and rod 52 will rotate 30 about the axis of rod 52, which, of course, corresponds with the axis of sleeve 36 which serves as a bearing for the rod 52. As the thickness of the work increases in passing from the breast to the rear of the heel, and as 35 it decreases in passing in the opposite direction, rod 52 will move axially of sleeve 36, plate 20 being correspondingly adjusted downwardly or upwardly by the pressure controlling mechanism of the machine. At 40 all times, however, rod 52 will be restrained from tilting by sleeve 36. It should be noted, moreover, that owing to the fact that the bearing of the rod 52 upon the last pin 64 is substantially in alinement with the line of 45 drive of the fastenings, there will be no substantial tendency to tilt rod 52 or to force the work out of position as would occur if the support of the work were substantially out of alinement with the line of drive.

Having described the invention, what I claim as new and desire to secure by Letters Patent of the United States is:—

1. A work support for a fastening-inserting machine provided with a presser plate 55 against which the work is pressed during the insertion of fastenings, said work support comprising a carrier having means to present the heel of a shoe supported by said carrier with its tread face slightly inclined relatively to the presser plate and with the edge of the tread surface of the heel bearing upon the presser plate adjacent to the position in which a fastening is to be inserted, said carrier being arranged to permit rotation of 60 the shoe about an axis at right angles to the

tread surface of said heel so as to maintain said inclination throughout the insertion of a group of fastenings parallel to the edge of the heel, and a support upon which the carrier directly rests, said support being substantially 70 in alinement with the line of drive of the fastenings.

2. A work support for a fastening-inserting machine provided with a presser plate against which the work is pressed during the insertion of fastenings, said work support comprising a last pin inclined to the tread face of the heel of a shoe mounted upon a last carried by said last pin and located to present the heel of such a shoe with its tread face slightly inclined relatively to the presser plate and with the edge of the tread surface of the heel bearing upon the presser plate adjacent to the point at which a fastening is to be inserted, a carrier for the last pin 75 arranged to permit rotation of the last pin and shoe about an axis at right angles to the tread surface of said heel so as to maintain said inclination throughout the insertion of a group of fastenings parallel to the edge 80 of the heel, and a solid support for said carrier substantially in alinement with the line of drive of the fastenings.

3. A work support for a fastening-inserting machine provided with a presser plate 95 against which the work is pressed during the insertion of fastenings, said work support comprising a rod, a shoe holder carried by said rod arranged to present the heel of a shoe carried thereby with its tread surface 100 slightly inclined relatively to the presser plate of the machine and with the edge of the tread surface of the heel bearing against the presser plate adjacent to the point at which a fastening is to be inserted, a bearing for said rod arranged to permit both bodily and rotary horizontal movement of the rod and the shoe holder about an axis at right angles to the tread surface of the heel so that the inclination of the tread surface of the heel to the 105 presser plate may be maintained throughout the insertion of a series of fastenings parallel to the edge of the heel, and a support upon which the lower end of the rod directly rests, said support being substantially in alinement 110 with the line of drive of the fastenings.

4. A work support for a fastening-inserting machine provided with a presser plate against which the work is pressed during the insertion of fastenings, said work support comprising a rod, a last pin carried by said 115 rod, said last pin being inclined at an angle to the tread face of the heel of a shoe mounted upon a last carried by said last pin and located to present the heel of such a shoe with its tread surface slightly inclined relatively to the presser plate of the machine and with the edge of the tread surface of the heel bearing against the presser plate adjacent to the point at which a fastening is to be inserted, 120

5 a bearing for said rod arranged to permit both bodily and rotary horizontal movement of the rod and last pin about an axis at right angles to the tread surface of the heel so that the inclination of the tread surface of the heel relatively to the presser plate may be maintained throughout the insertion of a series of fastenings parallel to the edge of the heel, and a solid support for the lower end 10 of the rod substantially in alinement with the line of drive of the fastenings.

15 5. A work support for a fastening-inserting machine provided with a presser plate against which the work is held during the insertion of fastenings, said work support comprising a carrier adjustable to present the heel of a shoe supported by said carrier with its tread face alternately parallel to the presser plate of the machine or slightly 20 inclined thereto, with the edge of the tread surface of the heel bearing upon the presser plate adjacent to the position at which a fastening is to be inserted, said carrier being arranged to permit rotation of the 25 shoe about an axis at right angles to the tread surface of the heel so as to maintain said parallel or inclined relation throughout the insertion of a group of fastenings parallel to the edge of the heel while the shoe 30 is directly supported on the carrier with its heel seat considerably inclined to the line of drive of the fastenings, and a solid support for said carrier substantially in alinement with the line of drive of the fastenings.

35 6. A fastening-inserting machine having, in combination, means for carrying a shoe in which fastenings are to be inserted mounted for universal horizontal movement and restrained from tilting movement, said means 40 including a rod alternatively, according to the class of work being operated upon, either substantially in alinement throughout its length with the line of drive of the fastenings or slightly inclined thereto, and a support for said means substantially in alinement with the line of drive of the fastenings.

45 7. A fastening-inserting machine having, in combination, a last pin arranged to carry a shoe, in which fastenings are to be inserted mounted for universal horizontal movement and restrained from tilting movement, said last pin being inclined to the line of drive of the fastenings, and a support for the last pin substantially in alinement with the line of 50 drive of the fastenings.

55 8. A work support for a fastening-inserting machine, comprising a last pin, means on which said last pin is mounted for universal horizontal movement, means for preventing tilting of said last pin, said last pin being inclined to the line of drive of the fastenings, and means for supporting said mounting means and last pin arranged substantially in alinement with the line of drive of the fastenings.

9. A work support comprising a member having a substantially horizontal upper surface, a rod having its lower end resting on said member and horizontally movable in any direction relatively thereto, a last pin rigidly secured to said rod, and means for preventing tilting of said rod while permitting it to be moved horizontally.

10. A work support comprising a member having a substantially horizontal surface, a 70 rod having its lower end bearing upon and supported by said surface and horizontally movable in any direction relatively thereto, shoe supporting means carried by said rod, a bearing for said rod engaging said rod between its ends and arranged to permit both lengthwise and rotary movement of the rod in the bearing, and a support for said bearing arranged to permit horizontal movement of the bearing and rod while preventing tilting of the bearing and rod.

11. A work support for a fastening-inserting machine comprising a last pin, a rod to which said last pin is adjustably but rigidly secured, a shaft, a member having a substantially horizontal upper surface carried by said shaft and against which the lower end of said rod bears, and means arranged to prevent tilting of said rod while permitting horizontal movement in any direction over said 95 member.

12. A work support for a fastening-inserting machine comprising a carrier, a last pin rigidly carried thereby, said last pin being inclined to the line of drive of the fastenings, 100 a shaft, a member carried by the upper end of said shaft and arranged to support said carrier for horizontal bodily movement, and means for preventing tipping of the carrier and last pin while permitting said horizontal movement of the carrier and last pin relatively to said member.

13. A work support for a fastening-inserting machine comprising a last pin, said last pin being inclined to the line of drive of the fastenings, a carrier for said pin rigidly secured thereto, a plate arranged to support said carrier, means for preventing tilting movement of the last pin and carrier arranged to permit relative horizontal movement of the carrier and the plate and to permit rotary movement of the last pin and carrier, and a spring tending to rotate the last pin and carrier to a predetermined position.

14. A work support for a fastening-inserting machine comprising a last pin, a slightly inclined rod to the upper end of which said last pin is adjustably secured, a vertical shaft, a plate carried by the upper end of said shaft and supporting the lower end of said rod, 125 and a member mounted for movement within prescribed limits and arranged to prevent tilting of said inclined rod while permitting horizontal movement in any direction over said plate.

15. A work support for a fastening-inserting machine comprising a last pin, a carrier therefor, a shaft, a plate carried by the upper end of said shaft to support said carrier and having an elevated rim to limit relative movement of said carrier and said plate, and means for preventing tipping of the carrier and last pin while permitting horizontal movement of the carrier and last pin relatively to said plate. 5 70
16. A work support for a fastening-inserting machine comprising a last pin inclined to the line of drive of the fastenings, a carrier for said pin rigidly secured thereto, a plate arranged to support said carrier means for preventing tilting movement of the last pin and carrier arranged to permit relative horizontal movement of the carrier and the plate and to permit rotary movement of the last pin and carrier about an axis nearly at right angles to the surface of said plate, and means tending to rotate the last pin and carrier to a predetermined position. 15 80
17. A work support for a fastening-inserting machine comprising a bracket pivoted to the frame of the machine for limited movement about a horizontal axis, an arm pivoted to said bracket for movement relatively thereto about a horizontal axis at right angles to said first-named axis, a shaft, a plate carried by the upper end of said shaft, a rod having its lower end supported by said plate and carrying at its upper end a last pin, and a bearing for said rod carried by said arm and arranged to permit both longitudinal and rotary movement of said rod relatively to said bearing. 20 90
18. A work support for a fastening-inserting machine comprising a shaft, a plate carried by the upper end of said shaft and having an elevated rim, a rod having its lower end somewhat rounded, bearing upon and supported by said plate, and mounted for horizontal movement limited by the elevated rim of said plate, and a work support carried by said rod and movable therewith. 40 100
19. A work support for a fastening-inserting machine comprising a post, a bracket pivoted thereto for limited movement about a horizontal axis, an arm pivoted to said bracket for movement relatively thereto about a horizontal axis at right angles to said first-named axis, a shaft mounted for vertical movement in said post, a plate carried by said shaft, a rod having its lower end supported by said plate and carrying at its upper end a last pin, and a bearing for said rod carried by said arm and arranged to permit both longitudinal and rotary movement of said rod relatively to said bearing. 50 110
20. A work support for a fastening-inserting machine comprising a shaft, a plate carried by the upper end of said shaft, a rod having its lower end somewhat rounded and bearing upon and supported by said plate, 65 120
- said rod being mounted for horizontal movement relatively to said plate and restrained from tilting, and a work support rigidly secured to said rod and movable therewith, said plate having an elevated rim to limit the horizontal movement of the rod and work support. 70
- In testimony whereof I have signed my name to this specification.
